UNITED STATES PATENT OFFICE.

LEIGH MOYLE, OF ST. LOUIS, MISSOURI.

LANTERN.

No. 831,291.

Specification of Letters Patent.

Patented Sept. 18, 1906.

Application filed March 29, 1906. Serial No. 308,642.

To all whom it may concern:

Be it known that I, LEIGH MOYLE, a citizen of the United States, residing in the city of St. Louis, in the State of Missouri, have invented certain new and useful Improvements in Lanterns, of which the following is a full, clear, and exact description, reference being had to the accompanying drawings, forming part of this specification.

10 My invention relates to a globe-lifting attachment for tubular lanterns, and it has for its object to provide a simple and efficient means whereby the globe may be readily lifted and lowered, guided during its movement, and supported when in uplifted position.

Figure I is an elevation of a lantern equipped with my globe-lifting device, the globe being shown in lowered position. Fig. II is a 20 horizontal section taken on line II II, Fig. I. Fig. III is an elevation of a part of the lantern and the lifting device, the lifting device being shown in the position assumed when the globe is in uplifted position.

25 A and A' designate the air-tubes of a tubular lantern, that may be of any common construction. One of these air-tubes—for instance, that A—is provided with a notch a.

B is the lantern-globe, that is seated upon 30 the ordinary globe-plate C.

1 designates a guide member suitably attached to the globe-plate C and preferably formed of wire. This guide member extends laterally from the globe-plate in a direction 35 toward the air-tube A', and it is bifurcated, as seen at 2, Fig. II, to provide for its engagement in order that the member will straddle said air-tube to permit vertical movement of the guide member on the tube and partially 40 restrain the globe-plate from lateral movement.

3 designates a lift-arm, the inner portion of which is secured to the globe-plate C, while the outer portion of the arm extends laterally 45 from the globe-plate and upwardly into juxtaposition with the air-tube A. The lift-arm 3 is constructed of wire partially folded upon itself, and it is provided at its outer and upper end with a loop 4, which surrounds the 50 air-tube A to ride thereon in a vertical direction and serve as a holding member for the globe and globe-plate of the lantern during

the actions of lifting and lowering them. The upwardly-extending portion of the lift-arm 3, which is of folded form, straddles a bead a' 55 at the inner edge of the air-tube A, thereby causing said portion of the lift-arm to serve as a guide member for the globe B and its plate during vertical movement thereof and also preventing lateral movement of the lift-arm. Projecting from the loop 4 of the lift-arm is a finger-piece 5.

6 designates a finger-piece that is secured to the air-tube A above the loop of the lift-arm.

65 In the use of my lifting device the operation of the parts is as follows: Assuming the globe B and the plate on which it is mounted to be in the lowered position illustrated in Fig. I, the globe is lifted by the operator placing a 70 thumb of his hand upon the finger-piece 6 and placing a finger beneath the finger-piece of the loop 4. The operator then exerts a pull upon the loop finger-piece and elevates the loop, the lift-arm by which it is carried, 75 the globe-plate and globe, and the guide member 1 until the loop of the lift-arm has been raised to the notch a in the air-tube A in order that the loop may enter thereinto and be retained in its uplifted position, due to 80 such engagement, whereby all of the parts are held suspended until it is desired to lower them. When the parts are to be lowered, the operator exerts pressure against the finger-piece 5 of the loop-arm in an outward direction, 85 and the loop is forced from the notch a, thereby permitting it to be lowered with the lift-arm and other parts.

I claim—

1. The combination in a lantern having a 90 pair of air-tubes, and a globe-plate; of a wire lift-arm secured to said globe-plate and provided with a vertically-elongated guide portion engaging one of said tubes and a loop at the upper end of said guide portion encircling 95 the guide-engaged tube; said air-tube being provided with a notch to receive said loop, substantially as set forth.

2. The combination in a lantern having a 100 pair of air-tubes, and a globe-plate; of a wire lift-arm secured to said globe-plate and having a folded vertically-elongated guide portion extending upwardly from said plate and engaging one of said air-tubes, and having a

loop at its upper end encircling the guide-engaged tube, substantially as set forth.

3. The combination in a lantern having a pair of air-tubes, and a globe-plate; of a wire lift-arm secured to said globe-plate and provided with a vertical elongated guide portion engaging one of said tubes and a loop at the

upper end of said guide portion encircling the guide-engaged tube, substantially as set forth.

LEIGH MOYLE.

In presence of—

NELLIE V. ALEXANDER,
BLANCHE HOGAN.
